UNITED STATES PATENT OFFICE

WILLIAM W. MCCORD, OF WYANDOTTE, MICHIGAN, ASSIGNOR TO MCCORD RADIATOR & MFG. CO., OF DETROIT, MICHIGAN, A CORPORATION OF MAINE

ELECTRODEPOSITING APPARATUS

Application filed July 6, 1926. Serial No. 120,706.

This invention relates to electrodepositing apparatus.

One object of my invention is to provide the cathode in band form so that metal may be deposited on and stripped from both sides of the cathode to increase the production of the apparatus.

A further object of my invention is to make the cathode in endless band form and have it so disposed with respect to the electrolyte that there are portions in and out of the same, with the portion in the electrolyte comprising more than fifty per cent of the depositing surface of the cathode, so that metal of the desired thickness may be deposited on the cathode in less than a complete revolution thereof, thereby enabling the deposited metal to be continuously stripped from the portion of the cathode outside of the electrolyte during the rotation of the cathode therethrough.

Another object of my invention is to provide a trough to contain the electrolyte and have the cathode extend edgewise downward into the same, with the trough following the shape or contour of the cathode but having its ends spaced apart so as to expose the portion of the cathode movable through the trough for stripping the deposited metal from the cathode.

A further object of my invention is to provide means whereby the deposited metal may be continuously and simultaneously stripped at this gap in the trough from the opposite sides of the cathode.

A further object of my invention is to have the circumferential length of the cathode such and have its rotation through the trough so timed that at any given amperage the deposit of metal on any portion of the cathode will be built up to the thickness desired in a space of time taken by that portion of the cathode to traverse the distance of submersion in the electrolyte, thereby allowing for continuous stripping of deposited metal from the cathode.

A further object of my invention is to provide the trough with two sets of outlets, one set adjacent the top of the trough and the other set at the bottom of the same so that

relatively short paths are provided for the circulation of electrolyte through the trough, thereby allowing for rapid circulation to avoid any possibility of having stagnant portions of electrolyte in the trough to interfere with or hinder the proper deposit of metal on the cathode faces.

Another object of my invention is to provide perforated anode plates on opposite sides of the electrolyte and to space such plates inward from the adjacent wall of the trough to provide chambers or compartments to receive the anode material, which may take the form of scrap metal and thus reduce the cost of production of the deposited metal.

A further object of my invention is to have these anode plates spaced equal distances from all points of the cathode so as to allow for even deposition of metal on the same.

A still further object of my invention is to provide an apparatus or unit which is simple in construction and operation.

The invention consists further in the matters hereinafter described and claimed.

In the accompanying drawings—

Fig. 1 is a top plan view of an electrodepositing apparatus or unit constructed in accordance with my invention;

Fig. 2 is an enlarged vertical sectional view taken on the indirect line 2—2 of Fig. 1;

Fig. 3 is an enlarged vertical section through the trough and cathode structure at one side of the same as on line 3—3 of Fig. 1;

Fig. 4 is an enlarged vertical sectional view with parts in perspective to illustrate certain details of construction;

Fig. 5 is a horizontal sectional view taken on line 5—5 of Fig. 6 to show the portion of the apparatus at the gap and illustrating the manner in which the deposited metal is continuously and simultaneously stripped from both sides of the cathode;

Fig. 6 is a vertical sectional view taken on line 6—6 of Fig. 5;

Fig. 7 is a perspective view of the flexible baffle and end assembly at one end of the trough, the upper portion of the cathode band being cut away to show the structure behind the same;

Fig. 8 is a diagrammatic top plan view of one of the depositing units to show that the trough does not extend clear around the cathode but extends more than half the circumference of the same; and

Fig. 9 is diagrammatic view illustrating how several units are connected for circulation of the electrolyte therethrough.

The apparatus or unit, as shown in the drawings, comprises an endless cathode 1 in band form and a trough 2 containing an electrolyte for the cathode, the latter extending edgewise downward into the electrolyte, as illustrated in Figs. 2, 3, and 4. The cathode 1 may be annular or circular in form and be disposed to rotate about a vertical axis. The trough 2 follows the shape of contour of the cathode 1 with the latter terminating short of the bottom wall of the trough, as shown in Figs. 2 and 3. The trough 2 does not extend continuously about the cathode, but has its ends spaced apart to provide a gap 3, as shown in Figs. 5 and 8, where the portion of the cathode movable through the trough is exposed to permit continuous stripping of the deposited metal from the cathode outside of the electrolyte as the cathode is revolved.

Perforated anode plates 4, 4 are arranged in the trough 2 on opposite sides of the cathode 1, as clearly shown in Fig. 3. These plates 4 are spaced inward from the upright side walls of the trough so that anode material, preferably scrap metal (copper scrap when copper is to be the deposited metal), may be introduced into the compartments provided in the trough behind the plates 4, as shown in Fig. 3. As illustrated in this figure, the cathode 1 extends into the space between the plates 4, thus permitting metal to be deposited from the electrolyte on both sides of the cathode to increase the productivity of the device. As shown in Fig. 8, the anode plates 4, 4 extend the full length of the trough and are spaced equidistant at all points from the portion of the cathode between them so as to secure a substantially even deposition of metal on both sides of the cathode.

The main support of the apparatus includes a number of uprights 5, 6 spaced apart about the trough 2 on opposite sides thereof, as shown in Figs. 1 to 3. These uprights extend above the trough 2 and the inner set 5 support a ring 7 inside of the cathode 1 and extending entirely about the same. An annular member or ring 8 is arranged above the ring 7 with antifriction bearing balls 9 between them so that the upper ring may easily rotate on the lower ring. The cathode 1 is suspended from the member 8 and the latter is rotated by any suitable power driven means. In the apparatus shown in the drawings, I provide the member 8 with a plurality of teeth 10 for mesh with a driv-

ing pinion 11, as shown in Figs. 1 and 6. Power is furnished to this pinion through a sprocket chain 12 from a main driving shaft 13, as shown in Fig. 6.

The cathode 1 is suspended from the member 8 by a plurality of brackets or hangers 14, suitably insulated from the ring and spaced apart about the same and having depending portions 15 to which the cathode 1 is directly secured, as shown in Fig. 3. A conductor ring 16 is carried by the brackets 14 outside of the cathode 1. Said ring 16 dips into liquid mercury contained in an annular channel 17 carried at the upper ends of the outer standards or uprights 5 outside of the cathode 1. The metal member in which the channel is formed is connected by leads 18 to a bus-bar 19 extending about the apparatus on the outside thereof and supported by the outer set of uprights 5, as shown in said Fig. 3. With the ring 16 dipping into the mercury, a frictionless electrical connection is made for the rotating cathode 1. The bus-bar 19 is connected with the negative pole of the generator (not shown), while the bus-bars 20, 20 on the opposite sides of the trough are connected with the positive pole of the generator. Flexible leads 21, 21 carry current from the bars 20 to the metal scrap 22 serving as the anode material in the trough 2. These leads have conductor rods 21^a, 21^a which are inserted into the scrap for contact therewith.

For circulating the electrolyte through the trough 2, I provide the latter with a plurality of outlets 23, 24, arranged in sets with the outlets 23 of one set at or adjacent the upper end of the trough and the outlets 24 of the other set at the bottom of the trough, as shown in Figs. 2 and 3. Said outlets are connected to a common return pipe 24^a located below the trough 2 and following the shape thereof. Said pipe 24^a is supported between the uprights 5, 6 by stools 24^b, as shown in Fig. 2. A main supply conduit 25 is located above the trough 2 and extends about the same on the inside of the cathode 1, as shown in Figs. 1 to 3. This conduit is supported by the inner uprights 6. Said conduit 25 is provided with a plurality of spouts 26 extending down to the trough 2 for discharging the electrolyte into the same. These spouts constitute the inlets of the trough and are spaced about the conduit 25 so as to discharge the electrolyte into the trough at a plurality of points in its length. As shown in Fig. 3, the spouts discharge into the trough 2 into one of the compartments for the anode material so as to constantly deliver fresh or revived electrolyte thereto. The spouts terminate relatively high above the normal level a of the electrolyte in the trough, so that no opportunity is afforded for the level to rise above the discharge ends of the spouts and hinder or stop the flow therefrom. The outlets 23 are all at

the same height above the bottom of the trough so as to determine the normal level of the electrolyte therein. The outlets 23, 24 and the inlets 26 of the trough are distributed 5 along the length of the same and are included in the circulating system so that the electrolyte may be circulated rapidly through the trough in relatively short paths. This will avoid any possibility of having any stagnant 10 electrolyte in the trough to interfere with the efficient depositing of metal on the cathode 1. The trough 2 does not extend clear around the cathode 1, but is longer than half the circumferential length thereof, as shown in Fig. 15 8. With the cathode rotatable, the speed of rotation of the cathode may be so timed that at any given amperage the deposit of metal on any portion of the cathode will be built up to the thickness desired by the time taken 20 by that portion of the cathode to traverse the length of the trough. Thus metal of the desired thickness may be deposited on the cathode 1 in less than one complete revolution of the same, thereby making the deposited 25 metal ready for stripping when it reaches the gap 3 between the ends of the trough. Due to this fact, the deposited metal may be continuously stripped from the portion of the cathode in the gap 3) while metal 30 is being deposited on the other portion of the cathode in the trough. With both sides of the cathode accessible at the gap 3, the deposited metal may be simultaneously stripped from both sides of the cathode during the 35 rotation thereof.

This I have shown in Fig. 5. As there illustrated, the deposited metal is stripped from both sides of the cathode in the form of continuous webs 27, 27 and wound up in reels 40 28, 28 on the opposite sides of the cathode. For this purpose, two upright spindles 29, 29 are arranged on opposite sides of the trough 2 at the end of the same from which the cathode leaves the trough. These spindles 45 are power driven from the main drive shaft 13 in any desired way, meshing bevel gears 30, 31 being shown by way of example for each spindle in Fig. 6. I may employ suitable friction connection (not shown) in the 50 drive to the spindles to allow for the change in diameter as the reels increase in size. To disconnect the cathode 1 from the power driven means whenever desired, I provide a suitable hand-operated clutch 32 in the driving connections, as shown in Fig. 6.

To prevent undue leakage of the electrolyte from the trough 2 at the ends thereof where the cathode 1 enters and leaves the trough, respectively, I provide a suitable 55 form of baffle means. The structure is illustrated generally in Fig. 5 and more in detail in Fig. 7. As shown, the baffle means at the entrance end of the trough extends into the same, while the baffle means at the exit end 60 of the trough extends out of the same. The

baffles have wiping contact with the cathode, and the structure is substantially the same as the opposite ends of the trough. At each end of the trough I provide a plurality of flexible strips 33, 34 bearing against the cathode 1 on opposite sides thereof and extending upward from the bottom of the cathode to above the level of the electrolyte in the trough. (See Fig. 7.) The strips at each end of the trough are arranged in inner 70 and outer sets, with the strips 33, 33 composing the outer set and the strips 34, 34 the inner sets. These strips are preferably of rubber, and are suitably held at the framework forming the ends of the trough. The outer strips 33 at the exit end of the trough are pressed with considerable pressure against the opposite sides of the cathode, and for this purpose I employ spring means, which as shown in Fig. 7 comprises metal members 80 35 bearing against the outside of the strips 33 and extending substantially the full length thereof. These members 35 have a plurality of outwardly projecting rods 36 supported by an upright bar 37 attached to the adjacent outer upright 5 or 6 of the main frame of the apparatus by flat springs 37a. These springs force the associated members 35 against the baffles 33 through coiled springs 38 on the rods, as shown in Fig. 5. 95

A gutter 39 is arranged below the lower edge of the cathode 1 between the ends of the trough 2 to catch any electrolyte which leaks past the baffles 33, 34. This gutter has outlets 40, 40 in its bottom wall, with the 100 outlets connected with certain circulating pipes or conduits of the system.

The receptacles for the anode material 22 are closed at the ends of the trough 2 by end walls 41, 41, as shown in Fig. 7. These walls extend between the side walls of the trough and the anode plates 4, 4. The walls 41, 41 are held in place by a suitable structure 42, 42. This also fixes the flexible baffles 33, 34 to the end walls 41, and clamps the inner baffles against the adjacent edges of the plates 4 to make leak proof joints for the ends of the anode compartments. 105 110

The cathode band 1, as shown in Fig. 3, terminates short of the bottom wall of the trough 2. An insulating strip or piece 43 is fixed to the lower edge of the cathode to prevent metal from being deposited about its lower edge to hinder stripping from the cathode. The portion of the cathode at the 115 level of the electrolyte in the trough may be coated with bands 44 of insulating paint applied to the cathode where it is exposed at the gap 3. These bands extend slightly above and below the level of the electrolyte and define upper edges for the deposited metal on the cathode. 120 125

I have found that satisfactory results may be obtained in a system containing three units A, B, C, as shown in Fig. 9. Each unit is 130

made as heretofore described and shown. With three units I use three storage tanks 45, 46, and 47 which are disposed to be on the same level. Tank 45 delivers electrolyte to unit A through a pipe or conduit 48, in which is a motor operated force pump 49 which withdraws electrolyte from said tank. Pipe 48 leads to the main inlet pipe 25 of unit A, as shown.

10 Tank 46 delivers electrolyte to unit B through a pipe or conduit 50 which leads to the inlet pipe 25 of unit B. Tank 47 delivers electrolyte to unit C through a pipe or conduit 51 which is connected with the inlet pipe 25 of that unit. In each of pipes 50 and 51 there is a motor operated pump 49 for withdrawing electrolyte from the respective tanks and forcing it through these pipes.

20 The return flow from the several units is back to the tanks. These are connected for communication with each other by conduits 52, 53. These connections are so arranged that one tank siphons to the next, thus avoiding the use of force or other pumps in the 25 connections. With the pumps withdrawing electrolyte from the respective tanks, the levels in the tanks vary. This makes the head of the liquid in one tank higher than in another and the siphons act to create a flow 30 from the high to the low tank and reverse as the levels reverse.

35 The return from each unit is to a tank not directly delivering to the unit. As shown in Fig. 9, unit A has its lower pipe 24^a connected with tank 46 by a return pipe 54. Unit B makes return to tank 47 from its pipe 24^a through a pipe 55; while unit C makes return to tank 46 from its pipe 24^a by pipe 56.

40 The outlets 40, 40 of the gutters 39 of the several units drain back to a single tank, as 45, as shown in Fig. 9. To accomplish this, each unit A, B, C has a drain pipe 57, all of which connect with a single pipe 58 leading back to tank 45. As shown in Fig. 9, the 45 gutter 39 of each unit has a number of outlets 40, one set being directly connected with the drain pipe 57 of the unit. The other outlets 40 are connected with their drain pipe 57 by branches 59, 59, as shown. For the 50 sake of clearness of illustration in Fig. 9, I have not shown the spouts 26 with which the inlet pipes 25 are provided. It is to be of course understood that these pipes are provided with these spouts in order to discharge 55 the electrolyte into the troughs 2 of the several units A, B, C.

By the arrangement shown and described, there is a continuous and uninterrupted flow or circulation of electrolyte through all of 60 the units. By reason of the pumps 49, which are power driven, and the plurality of outlets 23, 24 in each unit, the circulation of the electrolyte through the several units is relatively rapid, so that no opportunity is afforded for quiet or stagnant spots along the

cathode to hinder the deposition of metal on the cathode. Moreover, the cathode of each unit is spaced a substantially equal distance from its anode plates 4, 4 throughout the full length of the latter so as to effect a substantially equal deposit of metal on both sides of the cathode in its travel through the electrolyte. 70

At least one of the units of the system is not supplied with anode material so that the 75 excess metal content produced in the electrolyte by the other units will be deposited out in the first mentioned unit to keep the metal content of the electrolyte substantially constant. This feature is disclosed and 80 claimed in my prior Patent No. 1,543,861, granted June 30, 1925.

To facilitate continuous stripping of the deposited metal from both sides of the cathode 1 during the rotation thereof, I make the 85 cathode of a metal or material, such as lead, aluminum or bronze, to which the deposited metal will not adhere in such manner as to hinder easy release therefrom. I have found that lead possesses this characteristic, thus 90 making it unnecessary to coat the cathode with grease or other substance to facilitate easy stripping of the deposited metal. The anode plates 4, 4 may also be of lead, and when so made the lower edges of said plates 95 are secured to the metal bottom wall of the trough 2 by fusing or burning. The upper edges of the plates 4 are flanged or turned over supporting rods 60, as shown in Fig. 7. I have found in building the apparatus as disclosed herein that high antimonial lead of a 100 sufficient thickness will support the weight of the electrolyte and anode material without buckling.

Units constructed and operated and connected for electrolytic flow in accordance with my invention enable metal to be deposited on the cathodes and be readily stripped therefrom in continuous sheet or web form during the rotation of the cathodes. Moreover, by depositing metal simultaneously on both sides of the cathode and stripping the deposited metal from the opposite sides of the rotating cathode, the rate of production of each unit is increased. The 115 units are simple in construction and operation and are especially well suited to use scrap metal as the anode material, thereby saving in that item alone. The upper ends of the anode compartments are open so that 120 scrap metal may be easily placed or dumped into the same at the start of the unit as well as during its operation.

In Fig. 1, I have shown an electric motor 61 located inside of the inner uprights 6, 6 and 125 connected through a suitable gear reduction 62 with the main shaft 13 for driving the same.

The details of structure and the arrangement of parts shown and described may be va- 130

riously changed and modified without departing from the spirit and scope of my invention. Those portions of the structure of the apparatus in the electrical connection with the anode are suitably insulated from those in the electrical connection with the cathode. In the actual machine which has been built, particular attention has been paid to insulating these various parts. Sheet fiber, fiber washers, and where bolts are to go through, fiber bushings through which bolts pass have all been used wherever there seemed to be any chance of grounding or shortcircuiting. The small scale on which the drawings of the application have of necessity been prepared, has prevented the showing of every place of insulation, but it is of course to be understood that insulation is used wherever required in an apparatus of this character.

20 I claim as my invention:

1. In an electro-depositing apparatus, the combination with an endless cathode, of a trough containing an electrolyte for the cathode and following the contour thereof, said cathode being in band form and extending edgewise downward into the trough for the deposit of metal on the portion of the cathode in the trough, said trough having a gap between its ends to expose the portion of the cathode movable through the trough, so that the metal deposited on the cathode may be continuously stripped therefrom in the gap, and means for moving the cathode through the trough.

35 2. In an electro-depositing apparatus, the combination with an endless cathode, of a trough containing an electrolyte for the cathode and following the contour thereof, said cathode being in band form and extending edgewise downward into the electrolyte in the trough for the deposit of metal simultaneously on the opposite sides of the cathode, said trough having a gap between its ends to expose the portion of the cathode movable through the trough so that the metal deposited on the cathode while in the trough may be continuously and simultaneously stripped from the opposite sides of the cathode in the gap, and means for moving the cathode through the trough.

50 3. In an electro-depositing apparatus, the combination with a support, of an annular member horizontally disposed and mounted on the support for rotation about a vertical axis, an annular cathode in band form suspended from and carried by said member, gear teeth on said member, and a driving gear meshing with said teeth for rotating said member.

55 4. In an electro-depositing apparatus, the combination with an endless cathode, of a trough following the shape of the cathode and containing an electrolyte therefor, said cathode being in band form and extending downward edgewise into the electrolyte in said

trough, said trough having a gap between its ends to permit of continuous stripping of the deposited metal from the cathode in the gap, and flexible baffles forming the ends of the trough and bearing against the cathode to retain the electrolyte in the trough.

70 5. In an electro-depositing apparatus, the combination with an endless cathode, of a trough following the shape of the cathode and containing an electrolyte therefor, said cathode being in band form and extending edgewise downward into the electrolyte in said trough, said trough having a gap between its ends to expose a portion of the cathode movable through the trough, flexible baffles bearing against the opposite sides of the cathode where it enters and leaves the trough, respectively, said baffles being at the ends of the trough to close the same, means including a plurality of inlets and outlets distributed along the length of the trough and arranged to permit the circulation of electrolyte through the trough and co-operating with the baffles to maintain the electrolyte at a desired level in the trough, and means for moving the cathode through the trough.

75 6. In an electro-depositing apparatus, the combination with an endless cathode, of a trough following the cathode and containing an electrolyte therefor, said cathode being in band form and disposed to extend edgewise downward into the electrolyte in said trough, said trough having a gap between its ends to expose a portion of the cathode so that the deposited metal may be stripped therefrom, flexible baffles at the ends of the trough and bearing against the opposite sides of the cathode to prevent undue leakage of the electrolyte at the ends of the trough, a gutter arranged in the gap of the trough and below the cathode to carry off the electrolyte leaking past the baffles, and means for rotating said cathode.

80 7. In an electro-depositing apparatus, the combination with an annular cathode arranged for rotation about a vertical axis, of a trough for the cathode and containing an electrolyte therefor, said cathode being in band form and extending edgewise down into the electrolyte in the trough, said trough having its ends spaced apart to expose a portion of the cathode, and anode plates in the trough on opposite sides of the cathode and following the contour thereof from end to end of the trough, said plates being spaced inward from the trough walls to accommodate scrap metal between them, said plates being perforated to allow the electrolyte to reach the scrap behind them, and means for rotating said cathode.

85 8. In an electro-depositing apparatus, the combination with an annular cathode arranged for rotation about a vertical axis, of a trough following the shape of the cathode and containing an electrolyte therefor, said

cathode being in band form and extending edgewise downward into the electrolyte in the trough, and anode plates in the trough on opposite sides of the cathode and spaced equi-distant at all points therefrom to allow for even deposition of metal on the cathode, said plates being spaced inward from the trough walls to accommodate metal scrap between the same, said plates being perforated to allow the electrolyte to reach the scrap behind the same, and means for rotating said cathode.

9. In a connected electro-depositing system, the combination with a plurality of 15 electro-depositing units, each having a cathode in band form and an electrolytic bath therefor, of a storage common to all the units, and conduit means connecting the units and storage for the circulation of electrolyte therethrough, said means including a plurality of inlets and outlets distributed along the length of each cathode to obtain a rapid circulation of the electrolyte past the same in relatively short paths.

10. In a connected electro-depositing system, the combination with a plurality of 20 electro-depositing units, each having a cathode in band form and an electrolytic bath therefor, of a storage means for the electrolyte common to all the units, and conduit means connecting the units for the circulation of electrolyte therethrough, said means including a plurality of inlets and outlets distributed along the length of each 25 cathode so as to obtain rapid circulation of the electrolyte past the same in relatively short paths, certain of the units being supplied with anode metal so that the excess metal content supplied to the electrolyte by 30 such units will be deposited out in the unit not supplied with anode metal.

11. In a connected electro-depositing system, the combination with a plurality of 45 electro-depositing units, each having a cathode in endless band form and a trough containing an electrolyte for the same, certain of said units containing anode material of storage means for the electrolyte and common to all the units, and means including a 50 plurality of inlets and outlets distributed along the length of each trough for connecting the units and the storage in circulation; the inlets of each trough being arranged to discharge the electrolyte into the upper portion of the trough, and the outlets of each trough being arranged to allow for a rapid circulation of electrolyte in each trough and to maintain a desired level of electrolyte in the troughs.

12. In a connected electro-depositing system, the combination with a plurality of 55 electro-depositing units, each having a cathode in endless band form and a trough containing an electrolyte for the same, certain 60 of the units containing anode material, of

storage means for the electrolyte and common to all the units, and conduit means including a plurality of inlets and outlets distributed along the length of each trough for connecting the units and the storage 70 in circulation; the outlets for each trough being arranged in two sets, one set at the bottom of the trough, and the other set adjacent to the upper end thereof so as to assist in maintaining a predetermined level in 75 the trough.

13. In an electro-depositing apparatus, the combination with an endless cathode arranged for rotation about a vertical axis, of a trough following the contour of the cathode 80 and containing electrolyte therefor, said cathode being in band form and extending edgewise down into the electrolyte in the trough, perforated anode faces in the trough on opposite sides of the cathode and arranged to receive anode material behind the same, a conduit disposed above the trough and extending about the same for supplying electrolyte thereto, spouts connected with said conduit and spaced apart lengthwise of the same 85 for discharging electrolyte into the trough, outlets for the trough, and means for supplying electrolyte to said conduit.

14. In an electro-depositing apparatus, the combination with an endless cathode arranged for rotation about a vertical axis of a trough following the contour of the cathode and containing an electrolyte therefor, said cathode being in band form and extending edgewise downward into said trough, perforated anode faces in the trough on opposite sides of the cathode and arranged to receive scrap anode material behind the same, a conduit extending about the trough above the same and having a plurality of spouts arranged to discharge the electrolyte into the trough to the rear of one of the anode faces at a plurality of points spaced apart about the trough, outlets for the trough, and means for rotating said cathode.

15. In an electro-depositing apparatus, the combination with an endless cathode arranged for rotation about a vertical axis, of a trough following the contour of the cathode and containing electrolyte therefor, said cathode being in band form and extending edgewise downward into the trough, a pipe extending about the trough above the same and having a multiplicity of spouts for discharging electrolyte into the trough at a multiplicity of spaced points in the length thereof, outlets for said trough, a storage for the electrolyte, and conduits connecting the storage with said pipe and outlets for the circulation of the electrolyte through the trough from said storage.

16. In an electro-depositing apparatus, the combination with an endless cathode in band form and arranged for rotation about a vertical axis, of a trough following the contour

of the cathode and containing an electrolyte into which the cathode extends edgewise, said trough having a gap between its ends, a gutter in the gap below the cathode to collect the electrolyte leaking through the ends of the trough, a storage tank for the electrolyte, and conduit means connecting both the gutter and the trough to the storage for circulating electrolyte through the trough and returning electrolyte from the gutter.

17. In an electro-depositing apparatus, the combination with an annular-like cathode arranged for rotation about a vertical axis, of a trough containing an electrolyte for the cathode and following the contour thereof, said cathode being in band form and extending edgewise downward into the trough for the deposit of metal on the portion of the cathode in the trough, said trough having a length less than the full circumferential length of the cathode but greater than half of such length to provide a gap between the ends of the trough to permit of continuous stripping of the deposited metal from the cathode in the gap, and means for moving the cathode through the trough.

18. In an electro-depositing apparatus, the combination with a trough containing an electrolyte, of means whereby the electrolyte may be continuously discharged into the trough at the upper end thereof, and a plurality of outlets in the trough for the electrolyte and distributed along the length of the trough so that there may be a continuous circulation of electrolyte therethrough, said outlets being at the bottom and the top of the trough, respectively, to provide relatively short paths for the electrolyte to flow therethrough, with the upper outlets positioned to maintain a desired level for the electrolyte in the trough.

In testimony whereof I affix my signature this 1st day of July, 1926.

WILLIAM W. McCORD.
